ABSTRACT

A device used for fitting sail hanks of the spring-loaded type on to a forestay consists of a channel section magazine which fits over the stay and which carries on its outer surface the previously assembled spring hanks of a sail to be hoisted. The magazine member is held on the stay and upon hoisting the sail the hanks slide off the magazine member on to the stay, greatly reducing the time needed to effect a sail change.

HANK-LOADING DEVICE

This invention relates to a hank-loading device for use in fitting spring-loaded sail hanks or clips to a stay, for example a forestay of a sailing vessel.

The leading edge or luff of a head sail is commonly secured to a wire stay by means of spring-loaded hanks or clips which are attached to the luff of the sail and which clip onto the wire stay. Various types of spring-loaded sail hank are known, but the commonest type has a U-shaped portion which fits onto the stay, and which is closed by a spring-loaded piston, the piston being retracted by hand to release the hank from the stay.

To fit a sail to a stay it is necessary to clip the individual sail hanks to the stay, and this can be a difficult and time-consuming operation. An object of the present invention is to provide a hank-loading device which can be used to facilitate the fitting of spring-loaded sail hanks or clips to a stay by obviating the need to fasten each hank or clip individually to the stay.

Essentially, the present invention resides in a shaped magazine onto which the hanks or clips are preloaded preparatory to effecting a sail change. More specifically, the present invention provides a hank-loading device for use in fitting spring-loaded sail hanks or clips to a stay, comprising a channel-section magazine member adapted to fit over the stay, a handle for gripping the magazine member, and releasable means for retaining the magazine member on the stay, the magazine member having parallel outer surfaces on which sail hanks or clips may be assembled, and at least one of the said outer surfaces being provided with longitudinal guide means which retain the hanks or clips on the magazine member and permit longitudinal sliding movement of the hanks or clips along the magazine member.

It will be appreciated that use of the device according to the invention can greatly reduce the time required to effect a sail change, so that the device is particularly, but not exclusively, applicable to racing yachts. The hanks or clips of a sail are pre-assembled on the magazine member preparatory to hoisting the sail. When the sail is to be hoisted the magazine member is placed on the stay, having first lowered the existing sail, if any, and the appropriate halliard is attached to the head of the sail. Upon hoisting the sail the hanks or clips slide along the outer surfaces of the magazine member, leaving the magazine member and snapping in succession onto the stay.

Preferably the releasable retaining means are connected to a hinged part of the handle and are brought into a retaining position when the hinged part of the handle is gripped to hold the magazine member on a stay located in the channel of said magazine member.

The magazine member is preferably provided with a fixed handle part in addition to the hinged handle part, so arranged that when the two handle parts are gripped together the magazine member is retained on a stay by the releasable retaining means. The hinged handle part may be attached to the magazine member for pivotal movement about a hinge axis parallel to the longitudinal axis of the channel in the magazine member, said hinge axis being located laterally outwardly of one of the said outer surfaces of the magazine member. The hinged handle part preferably carries respective teeth at opposite ends of the magazine member, which teeth

enter the channel of the magazine member when the handle part is gripped, to hold the magazine member on a said stay.

The longitudinal guide means can conveniently comprise a longitudinally extending rib upstanding from one of the said outer surfaces, each hank or clip embracing said rib when assembled on the magazine member.

A removable stop is preferably located at one end of 10 the magazine member to prevent sliding movement of the hanks or clips off the magazine member from said end.

Preferably the channel-section magazine member has side walls which are formed with notches or recesses at one or both ends, so positioned that each hank or clip, when sliding off the magazine member, snap-engages a said stay located in the channel of the magazine member before leaving the magazine member.

A typical practical embodiment of the invention will 20 now be described, merely by way of example, with reference to the accompanying drawings, in which:

FIG. 1 is a diagrammatic perspective view of a hank-loading device according to the invention, illustrating its mode of use;

FIG. 2 is a diagrammatic side elevation of one half of the device shown in FIG. 1, the other half of the device being identical to the illustrated half and symmetrical with the latter about the line C-C;

FIG. 3 is an end elevation of the device shown in FIG. 2, and

FIG. 4 is a plan view of the illustrated half of the device shown in FIG. 2.

The illustrated hank-loading device is intended for 35 use in fitting spring-loaded sail hanks 1 (FIG. 1) of a headsail 2, part only of which is shown, to a wire forestay 3. The sail 2 and the hank 1 are of conventional construction, the hanks 1 being attached to the luff of the sail 2 at equal intervals. Each hank 1 has a C-shaped portion 4 which engages the stay 3, and a spring-loaded plunger 5 which closes the C-shaped portion 4 to retain the hank 1 on the stay 3. The hank 1 is released from the stay 3 by manually withdrawing the plunger 5 against the action of its biasing spring.

Normally the sail 2 would be attached to the stay 3 by engaging each of the hanks 1 individually with the stay 3, a process which is necessarily time-consuming.

The device according to the invention, illustrated in 50 use in FIG. 1, can greatly reduce the time required for a sail change. The device includes a channel-section magazine member 6 formed with two laterally outwardly projecting parallel flanges 7, 8 along its longitudinal edges. The size of the channel in the member 6 is such as to accommodate the stay 3 in the bottom of the channel, which has a semi-circular cross section for this purpose. The channel in the member 6 has plane parallel side walls with parallel outer surfaces 9 the spacing between which is such as to allow individual spring-loaded hanks 1 to be clipped onto the magazine member 6, in spring-loaded engagement with the parallel surfaces 9. One of the surfaces 9 is formed with a longitudinally extending upstanding rib 10 (FIG. 3) spaced from the respective flange 8. The individual hanks 1 when fitted to the magazine member 6 are retained thereon by the rib 10, which acts as a guide permitting longitudinal sliding movement of the hanks 1 along the magazine member 6.

Where the magazine member 6 is formed from sheet steel the upstanding rib 10 is conveniently formed during the folding operation, at the same time as the flanges 7, 8, as illustrated in FIG. 3.

The device is provided with a handle having a fixed part 11 and a hinged part 12 attached to the magazine member 6. The fixed handle part 11 consists of a bent metal bar of circular cross section attached by welding or brazing to opposite ends of the flange 7. The hinged handle part 12 is also formed from a metal bar in the same shape as the fixed handle part 11, opposite ends of the hinged part 12 being attached to respective hinge arms 13 which are pivotally attached by respective hinge pins 14 to respective brackets 15 attached by welding or brazing to opposite ends of the flange 8, the hinge pins 14 defining a hinge axis H which is parallel to the longitudinal axis of the channel in the member 6 and spaced laterally therefrom.

Each hinged arm 13 is formed integrally with a tooth 16 which engages in the channel of the magazine member 6 when the hinged handle part 12 is brought into juxtaposition with the fixed handle part 11, as illustrated in FIG. 2. The two teeth 16, positioned at opposite ends of the channel, prevent removal of the magazine member 6 from the stay 3 while the two handle parts 11, 12 are in this closed position.

The device can be opened, to permit fitting of the magazine member 6 to and its removal from a stay 3, by simply moving the hinged handle part 12 away from the fixed part 11, thereby removing the teeth 16 from the channel in the magazine member 6.

One of the flanges, 8 (FIG. 4), is provided at opposite ends with a circular hole 17 which is adapted to receive a bolt 18 (FIG. 1) designed to act as a stop preventing removal of hanks 1 from the magazine member 6 at the end fitted with the bolt 18.

When using the device the hanks 1 of a foresail are first clipped onto the magazine member 6, as previously described, while the sail is still located in its sail bag, preferably below decks. To prevent sliding of the hanks 1 off the magazine member 6 the hole 17 in the flange 8 opposite that in which the stop bolt 18 is located is engaged by one of the hanks 1, this hank being removed and fitted to the magazine member 6 immediately prior to hoisting of the sail 2. The sail, still in its bag, is brought into position on the foredeck, and with the existing headsail, if any, still hoisted, the tack of the sail 2 is attached to the appropriate fitting at the lower end of the stay 3, and a new sheet or sheets are rove off and bent onto the clew of the sail 2. Immediately the existing sail has been lowered, and before its hanks are detached from the stay 3, the magazine member 6 is fitted onto the stay 3 above the lowered sail and the two handle parts 11, 12, gripped together, to retain the magazine member on the stay. The appropriate halliard is attached to the head of the sail 2 and the sail 2 hoisted, whereupon the individual hanks 1 are withdrawn in succession from the magazine member 6 and snap automatically onto the stay 3. When the sail has been hoisted and all the hanks 1 have left the magazine member 6, the hinged handle part 12 is moved away from the fixed part 11 and magazine member 6 removed from the stay 3.

To ensure that each individual hank 1 does not leave the magazine member 6 before its plunger 5 has sprung home, the opposite ends of the side walls of the channel in the member 6 are provided with notches or recesses

19 at the position occupied by the plungers 5, so that the plungers move into their locking positions immediately before the hanks leave the magazine member.

The device according to the invention is particularly suitable for use in single handed yachts. For this purpose the device may be provided with releasable locking means for locking the magazine member on the stay. Such locking means may, for example, be associated with the two handle parts 11, 12.

10 It will be noted that the hank-loading device of this invention is intended for use with conventional spring-loaded sail hanks, and does not entail any modification to the hanks or the stay to which they are to be fitted. This is a practical, as well as an economic, advantage, 15 since in the event of loss or failure of the hank-loading device it is still possible to use the hanks and the stay in a conventional manner. This is in contrast to other previously known arrangements for effecting rapid sail changes in which conventional hanks are dispensed with in favour of slides engageable in a groove in a specially adapted stay.

20 Although the illustrated embodiment of the invention is fabricated in stainless steel, it may be found advantageous to manufacture the device in other materials, for example in plastics.

I claim:

1. A hank-loading device for use in fitting spring-loaded sail hanks or clips to a stay, comprising:

- a channel-section magazine member adapted to fit over the stay, the magazine member having parallel outer surfaces on which sail hanks or clips may be assembled;
- a handle for gripping the magazine member, said handle having a hinged part;
- releasable retaining means connected to said hinged part for retaining the magazine member on the stay, and
- longitudinal guide means on at least one of said outer surfaces, said guide means retaining the hanks or clips on the magazine member and permitting longitudinal sliding movement of the hanks or clips along the magazine member, said retaining means being brought into a retaining position when the hinged handle part is gripped to hold the magazine member on a stay located in the channel of said magazine member.

2. The device defined in claim 1, wherein the magazine member is provided with a fixed handle part in addition to the hinged handle part, the magazine member being retained on a stay by the releasable retaining means when said two handle parts are gripped together.

3. The device defined in claim 1, wherein said hinged handle part is attached to the magazine member for pivotal movement about a hinge axis parallel to the longitudinal axis of the channel in said magazine member, said hinge axis being located laterally outwardly of one of said outer surfaces of the magazine member.

4. The device defined in claim 2, wherein the retaining means comprise respective teeth carried by the hinged handle part at opposite ends of the magazine member, said teeth entering the channel of the magazine member when the fixed and hinged handle parts are gripped together.

5. A sail hank-loading device for use in fitting spring-loaded sail hanks or clips to a stay, comprising: a channel-section magazine member having a channel adapted to fit over the stay; releasable clamping means

for retaining the magazine member on the stay with the stay located in the channel of said magazine member, said magazine member having outer surfaces on opposite sides of the stay-receiving channel, which are parallel in the direction of the longitudinal axis of the channel and on which sail hanks or clips are assembled in use of the device, longitudinal guide means provided on at least one of the said outer surfaces for retaining the hanks on the magazine member while permitting longitudinal sliding movement of the hanks along the magazine member; a handle having a fixed part attached to the magazine member, and a part hinged to the magazine member, the releasable clamping means comprising teeth connected to the hinged part of the handle, which teeth enter the channel of the magazine member to retain a stay located in said channel when the hinged part and the fixed part of the handle are gripped together.

5 6. The device defined in claim 5, wherein the longitudinal guide means comprise a longitudinally extending rib upstanding from one of said outer surfaces, each hank or clip embracing said rib when assembled on the magazine member.

10 7. The device defined in claim 5, including a removable stop located at one end of the magazine member to prevent sliding movement of the hanks or clips off the magazine member from said one end.

15 8. The device defined in claim 5, wherein the channel-section magazine member has side walls which are recessed at at least one end, so positioned that each hank or clip, when sliding off the magazine member, snap-engages around said stay located in the channel of the magazine member before leaving the magazine member.
